UNITED STATES PATENT OFFICE

108,397

DESIGN FOR A COMBINED BOTTLE STOPPER AND LIQUID POURER

Clifford A. McBride, Riverside, and Percy J. Callowhill, Edgewood, R. I.; said Callowhill assignor to said McBride

Application August 21, 1937, Serial No. 71,224

Term of patent 14 years

To all whom it may concern:

Be it known that Clifford A. McBride and Percy J. Callowhill, citizens of the United States, residing, respectively, in Riverside, county of Providence, State of Rhode Island, and of Edgewood, county of Providence, and State of Rhode Island, have invented a new, original, and ornamental Design for a Combined Bottle Stopper and Liquid Pourer, of which the following is a specification, reference being had to the accom-

panying drawing forming a part thereof. In this drawing the figure is a perspective view of the combined bottle stopper and liquid pourer, showing our new design.

We claim:

The ornamental design for a combined bottle stopper and liquid pourer, as shown.

CLIFFORD A. MCBRIDE.
PERCY J. CALLOWHILL.
